UNITED STATES PATENT OFFICE

ELIHU D. WATT, OF LA GRANGE, ILLINOIS, ASSIGNOR TO RAYMOND CONCRETE PILE COMPANY, OF NEW YORK, N. Y., A CORPORATION OF NEW JERSEY

INTERNAL TAPERED PILE SHELL SECTION

Original application filed August 12, 1930, Serial No. 474,744. Divided and this application filed September 28, 1931. Serial No. 565,483.

This invention pertains to concrete piles, with particular reference to a thin concrete shell suitable for sinking into the ground to be filled with concrete to form a monolithic pile structure. This application is a division 5 of my application Serial No. 474,744, filed August 12th, 1930, entitled "Apparatus for driving internally tapered pile shell sections".

10 The present invention contemplates the formation of a cylindrical (non-taper) pile. Heretofore it has been customary to drive shells for such piles by hammer blows applied to the top of the shell. This required 15 the shell to be of considerable thickness in order to withstand the strains of driving, particularly the crushing strains where the end of shell sections contact with each other.

20 In order to save transportation and handling costs, it is desirable to make the shells as thin as possible. The principal object of the present invention is to disclose a thin concrete shell suitable for driving in such a manner as to avoid the above mentioned compressive stresses. In practicing 25 the present invention I arrange on a collapsible driving core a stack of similar concrete shell sections, each section being slightly tapered on its outer surface and made quite 30 tapered or conical on its inner surface by the insertion of a concrete lining gradually increasing in the thickness of its walls from top to bottom. The driving core is provided along its length with a plurality of tapered 35 surfaces each of which is adapted to accommodate and conform to the inner surface of a shell section. The core is driven from the top and each shell section is driven individually by the tapered core section with which it 40 is in contact.

45 Further and other objects and advantages will be apparent from the specification and claims, and from the drawings which illustrate what is now considered the preferred embodiment of the invention.

Fig. 1 shows the three-leaved driving core with its head.

Fig. 2 is a cross-section of a preferred form of shell section.

50 Fig. 3 is a cross-section of a stack of shell

sections after driving and before filling with concrete.

Fig. 4 shows the stack of shell sections on the expanded core, preparatory to driving.

Fig. 5 is a cross-section of a portion of a 55 finished pile.

Fig. 6 is an enlarged view, mostly in cross section, showing core and shell.

Fig. 7 is a view on the line 7—7 of Fig. 6.

60 The design of the shell section comprising the present invention may be understood by reference to Fig. 2, in which a very thin, slightly tapered annular metal casing 10 is lined with a thin layer of concrete 12 reinforced by steel rings 14. The concrete lining 65 of the shell section is made considerably tapered or conical on its inner surface by increasing the thickness of the walls thereof from a point adjacent the top of the section to the bottom thereof, and the upper end of 70 each casing 10 projects above the concrete lining so as to receive and overlap the lower end of the section above it when in assembled relationship, as shown in Figs. 3, 4, 5 and 6.

75 The driving core is of the collapsible type having three leaves 16, which may be moved outwardly or inwardly by toggles 18 connected to vertical axial shaft or rod 20 adapted for operation in well known manner by mechanism within driving head 22.

80 The surfaces of leaves 16 are so shaped that when they are assembled to form the core, they provide a series of tapered or conical surfaces, each adapted to engage a shell section of the kind shown in Fig. 2. The core is shown in Fig. 1 without shells, and in Figs. 4 and 6 with shells. In the last named figures the core is expanded to engage a stack 85 of shell sections, each section being engaged by a conical section of the core. Fig. 4 shows the assembly ready for driving, a shoe 24 being provided on the lower end with a casing 26 overlapping the lowest shell section.

90 It will be appreciated that when the assembly in Fig. 4 is driven by blows or pressure applied to head 22 the driving effect will be transmitted from the core to each shell section individually on account of their tapered 95 interrelationship, and it will not be necessary 100

to transmit force vertically from shell section to shell section.

After the driving operation is finished the core is collapsed and withdrawn, leaving a hollow shell in the ground as in Fig. 3. This shell is then filled with plastic concrete 28 as indicated in Fig. 5 to form with the shell sections a monolithic pile structure. Any spaces such as 30 (Fig. 3) between sections are filled by the plastic concrete as shown in Fig. 5.

It is to be understood that the invention is not limited to the specific embodiment herein illustrated and described, but may be used 15 in other ways without departure from its spirit as defined by the following claims.

I claim:

1. A pile shell comprising a slightly tapered annular body of thin material and a 20 lining fitted to the inner surface of the shell, said lining having its walls gradually increasing in thickness from the upper to the lower end thereof.
2. A pile shell comprising a slightly tapered annular body of thin material and a 25 lining fitted to the inner surface of the shell, said lining having its walls gradually increasing in thickness from the upper to the lower end thereof, and reinforcing means 30 embedded in the lining.
3. A pile section comprising an annular metallic shell of thin material and a lining within said shell leaving an uninterrupted core receiving bore, the outer surface of said shell being slightly tapered whereby the lower end will fit within the upper end of similar shell sections, the inner surface of said lining being considerably tapered to provide a positive driving surface for a driving core.

40 In testimony whereof I hereto affix my signature.

ELIHU D. WATT.
